UNITED STATES PATENT OFFICE.

MARTHA H. CONNOR, OF BALTIMORE, MARYLAND, ASSIGNOR TO THE TIN DECORATING COMPANY OF BALTIMORE, OF BALTIMORE, MARYLAND, A CORPORATION OF NEW JERSEY.

DESIGN FOR A BOX PART.

Application filed June 12, 1926. Serial No. 18,025. Term of patent 7 years.

To all whom it may concern:

Be it known that I, MARTHA H. CONNOR, a citizen of the United States, residing at Baltimore, in the State of Maryland, have invented a new, original, and ornamental Design for a Box Part, of which the following is a specification, reference being had to the accompanying drawing, forming a part thereof.

Fig. 1 is a top plan view of a box part showing my new design, the ornamental border being only partly shown, the com-

plete article involving the mere continuation of the same around the entire part.

Fig. 2 is an edge view with only a portion of the ornamental border on the periphery shown, it being understood that the unornamented portion involves a mere repetition of the ornamentation illustrated.

I claim:

The ornamental design for a box part as shown.

MARTHA H. CONNOR.
